CLAIM

The ornamental design for a flexible band, as shown and described.

DESCRIPTION

FIG. 1 is a first perspective view showing my new design in an unfastened configuration;

FIG. 2 is a top view of my new design in the unfastened configuration;

FIG. 3 is a bottom view of my new design in the unfastened configuration;

FIG. 4 is a front view of my new design in the unfastened configuration;

FIG. 5 is a back view of my new design in the unfastened configuration;

FIG. 6 is a left view of my new design in the unfastened configuration;

FIG. 7 is a right view of my new design in the unfastened configuration;

FIG. 8 is a second perspective view showing my new design in a fastened configuration;

FIG. 9 is a top view of my new design in the fastened configuration;

FIG. 10 is a bottom view of my new design in the fastened configuration;

FIG. 11 is a front view of my new design in the fastened configuration;

FIG. 12 is a back view of my new design in the fastened configuration;

FIG. 13 is a left view of my new design in the fastened configuration; and,

FIG. 14 is a right view of my new design in the fastened configuration.
